United States Patent Office.

JOHN B. DOUGHERTY, OF ROCHESTER, NEW YORK.

Letters Patent No. 92,591, dated July 13, 1869; antedated June 30, 1869.

IMPROVEMENT IN SHINGLE-MACHINE.

The Schedule referred to in these Letters Patent and making part of the same.

To whom it may concern:

Be it known that I, JOHN B. DOUGHERTY, of Rochester, in the county of Monroe, and State of New York, have invented certain new and useful Improvements in "Shingle-Machines;" and I do hereby declare that the following is a full, clear, and exact description thereof, reference being had to the accompanying drawings, making part of this specification, in which—

Figure 1 is a side elevation of an ordinary shingle-sawing machine, with my invention attached.

Figure 2 is a top view of the same.

Figure 3 is an end elevation of the frame, the hinged table and the sliding bolt-frame, or chuck G, being shown in section through the friction-rollers R and i, as indicated by the red lines n, fig. 2.

Figure 4 is an enlarged sectional view of the parts taken in the plane of the red line x, fig. 2.

Like letters indicate corresponding parts in the several figures.

This invention relates to that class of shingle-machines in which the bolt-carriage is operated by hand, presenting the block to a horizontal circular saw, and

It consists in the construction of the hinged frame, having carriage-ways, and carriage, and head-block arranged and operating thereon.

To enable others to make and use my invention, I will describe its construction and operation.

I make the frame A as heretofore used.

To the cap-rails B, I hinge the frame C, as seen at N, in fig. 1.

I provide this frame with a flange, F, to reach below the saw, and act as a guard, and also as a conductor of the sawdust.

The offset D is designed especially as a guide for the sawdust, as it is thrown from the block or bolt.

In these respects this frame or guard is similar to that shown in my former application, patented October 9, 1866.

This frame is made whole, and hinged so as to swing vertically from the saw, when desired.

There are clamping-jaws a cast on each side of the main frame A, and the head of the clamping-screw b, which is flattened, so as to have a shoulder only on two opposite sides, passes through between the jaws a, when the screws on each side of the machine is turned so as to clutch under the jaws, which hold this frame perfectly solid.

The ribs r of this frame are raised sufficiently to receive the friction-rollers R upon the top, and the rollers i, figs. 3 and 4, traverse the side of the track or rib r, on the right-hand side of the machine.

The lateral strain or friction, caused by the draught from the saw, is fully neutralized by the rollers i.

The jaws J, shown in figs. 3 and 4, secures the carriage G to the swinging frame C.

The counterweight w is intended to hold the frame C up out of the way, when the saw S is being removed or replaced, and the cord may be unhooked when the frame is adjusted in its working position.

The bolt-rest and dogging-apparatus, common in these machines, are not shown.

What I claim as my invention, and desire to secure by Letters Patent, is—

1. The swinging frame C, with carriage-ways r, and having the head-block or carriage G sliding thereon, all constructed to operate in the manner and for the purpose substantially as set forth.

2. The combination of friction-rollers R and i, jaws J, and carriage G, with the rails or ways r, in the manner substantially as described.

JOHN B. DOUGHERTY.
